ALL PURPOSE GRINDING APPARATUS

Arthur William Mall, Chicago, Ill.

Application October 10, 1936, Serial No. 105,073

2 Claims. (Cl. 51—178)

My invention relates to rail grinding apparatus and like devices.

My invention relates more particularly to a track rail grinder capable of use upon switch points, rail cross overs and other locations requiring a grinder that can be easily positioned for grinding at different angles if necessary.

The principal object of my invention is to provide an improved rail grinding apparatus of the type described that is readily portable, being mounted upon wheels adapted to roll on the stock rails of a railway track.

A further object is to provide in a rail grinding apparatus of the type mentioned conveniently operated means for changing the angle at which the grinding wheel can operate.

A further object is to provide improved means for laterally shifting the grinding wheel and associated parts.

20 A further object is to provide improved means for raising or lowering the grinding wheel and associated parts, capable of operating while the grinding wheel is being driven.

25 A further object is to provide improved mechanism for tilting the entire apparatus at a desired angle right or left to grind the vertical side walls of a switch point.

30 A further object is to provide improved mechanism associated with the drive of the grinding wheel whereby a flexible shaft takeoff may be connected thereto for driving other mechanism remotely placed therefrom.

35 A further object is to provide an improved frame structure whereby the grinding wheel, motor and supports are slidably and pivotally mounted thereon, yet capable of being fixedly positioned so the entire apparatus can be rolled forward and back on the railway tracks.

40 Other objects and advantages will be more apparent from the following description wherein reference is had to the accompanying seven sheets of drawings, upon which:

Fig. 1 is a side elevational view of my improved rail grinding apparatus;

45 Fig. 2 is a plan view thereof;

Fig. 3 is an enlarged plan view of the motor base, grinding wheel and associated parts shown in a changed position for grinding at an angle to the length of the machine;

50 Fig. 4 is a vertical sectional view of the same taken generally on the lines 4—4 of Fig. 3;

Fig. 5 is a vertical sectional view through the grinding wheel shaft and associated parts taken generally on the line 5—5 of Fig. 3;

Fig. 6 is an end elevational view of the horizontal frame and one of the end rollers;

Fig. 7 is a fragmentary sectional view showing the grinding wheel raising and lowering means and is taken generally upon the line 7—7 of Fig. 2;

Fig. 8 is an enlarged view of the outrigger and associated parts with one member of the rectangular frame shown in cross section and is taken generally on a line 8—8 of Fig. 2;

Fig. 9 is a fragmentary view showing a side elevation of a portion of the frame and the outrigger parts associated therewith;

Fig. 10 is a fragmentary plan section taken generally on the lines 10—10 of Fig. 8;

Fig. 11 is a side elevational view similar to Fig. 1 showing the motor, grinding wheel and associated parts in a raised position with a flexible drive associated therewith; and

Fig. 12 is a fragmentary plan view showing the manner in which the flexible drive is connected to the grinding wheel drive.

In the embodiment of my invention which I have chosen to illustrate, I provide a rectangular horizontal frame member 10 that may comprise the parallel spaced channel members 12 and 14 connected at their opposite ends by a pair of cross bars 16 and 18. The cross bars 16 and 18 may be formed with suitable bearing portions 20 and 22 extending downwardly therefrom and adapted to support suitable axle members 24 and 26. The track engaging rollers 28 and 30 are mounted upon the axles 24 and 26 respectively, and as shown, engage the top of the conventional track rail 32. The horizontal frame 10 as thus constructed is provided with the upright bar members 34 and 36 at one end and the bar members 38 and 40 at the other end. Each of the sets of bar members are connected together by suitable cross bars 42 and 44.

By welding the bar members to the channel members 12 and 14 and by welding the cross bars 42 and 44 across the extended ends, the upright frame is thus rigidly connected together and connected to the horizontal frame 10. The cross bars 42 and 44 are further connected together by suitable longitudinal brace members 46 and 48 thus providing a rigid frame construction capable of being grasped adjacent the upright end and movable from place to place. The uprights 34 and 36 may be formed with extended handle portions 50 which terminate in a cross bar 52.

For supporting the grinding wheel motor and associated parts I mount a horizontal cross shaft 54 in a pair of bearing members 56 and 58 se-

cured by bolt members to the inner sides of the channel members 12 and 14 of the horizontal frame. The shaft 54 may extend through a motor support member 56a which is mounted thereon for sliding movement sideways and for tilting movement about the same. The support member may have a portion 58a extending forward therefrom upon which an upright post 60 is integrally formed. The portion 58a may also be formed 5 with a horizontal slot 62 to receive a crank member 64 for a purpose which will be hereinafter described.

A motor base 66 is formed with a vertical housing 68 provided with the vertical bore 70 and is 15 adapted to be mounted upon the upright post 60 with the rear portion thereof supported upon a pad 72 formed on the member 56a directly above the cross shaft 54. In this manner the motor base and associated parts are free to be rotated about 20 the upright post 60 if desired.

I mount any suitable or desirable power means 25 upon the motor base 66. In the drawings I have shown a five-horse power gasoline engine E of any suitable design that is provided with a drive shaft 74 which extends through the side thereof. I provide the drive pulley 76 thereon, preferably formed with V-portions to drive the multiple V-belts 78 mounted thereon. The V-belts 78 are 30 adapted to be trained upon the driven pulley 80 that is keyed to the grinder wheel shaft 82.

The grinding wheel shaft and associated parts are mounted in a supporting bracket 84 that is secured to an extension 66a on the motor base 66. I provide suitable cap screws 86 for this purpose 35 which extend through elongated slots 88 in the bracket 84 to permit longitudinal movement of the pulley supporting bracket for the purpose of tightening the V-belts whenever the same become loose. A locking bolt 90 mounted upon one of 40 the extensions 92 of the bracket and passing through an ear 94 positioned thereon is adapted to bear against a shoulder 96 on the motor base and thus keep the bracket 84 in the locked extended position. The bracket 84 is formed with a yoke 45 portion having the two arms 92 previously mentioned which support the bearing housings 98 that carry suitable ball bearing members 100 for the shaft 82. I also provide the bearing housing coverings 102 provided with space to support 50 waste filled with lubricant so that the bearings are in effect self-lubricating. I mount a friction cone 104 upon one end of the shaft 82 and a plate 106 upon the reduced screw-threaded portion 107 at the opposite end. The plate 106 carries 55 a pair of grinding disc members 108 secured to the side walls thereof for vertical grinding upon the sides of rails and switch points. Suitable ear members 92a extending upwardly from the arm 92 to bracket 84 support a grindstone guard 60 110 which prevents sparks from flying off when the grinding wheel is in operation.

Means for raising and lowering the motor, the grinding wheel and associated parts (see Fig. 4) 65 may comprise the crank member 64 previously mentioned which extends through the horizontal slot 62 in the motor support 56. The crank 64 is adapted to extend horizontally between the channel members 12 and 14 and be mounted in suitable bearing brackets 112. Adjacent the 70 channel member 14 I provide a sector member 114 mounted upon the upper wall of the channel 14. I secure a plate 116 to the crank 64 and extend an operating lever 118 therefrom to a point adjacent the upper frame supports 46 and 48 75 where I provide a handle portion 120. A pawl

122 is securely fastened to the lever 118 and is formed with a tooth engaging the rack portion 114a of the sector 114. The lever 118 is formed of spring metal so that the tooth of the pawl can be sprung outwardly and be moved up or down 5 the rack as desired. In this manner the motor base 66 and all of its associated parts can be swung around the cross shaft 54 to raise or lower the grinding wheel 108 as desired.

Means for moving the motor base and associated parts horizontally around the vertical post 60 are also provided. I provide an arm 68a extending horizontally from the vertical post housing 68 and carrying at its upper end a pad 68b within which a bolt 124 is screw-threadedly 15 mounted. I also provide a pivot lever 126 secured against the flattened side 121 of the vertical post 60. I mount a pair of adjustment screws 128 and 130 upon the bolt member 124 and a pin 131 secured in the pivot lever 126. An adjusting 20 member in the form of a turnbuckle 133 connects the two screws together. In this manner, by turning upon the turnbuckle 133, thus drawing the centers of the bolts 124 and the pin 131 closer together or further apart as desired, the motor 25 base and its associated parts will be revolved about the vertical axis 60, thus moving the grinding wheel to a desired angle to operate upon switch points or other portions of rails.

Means for shifting the motor base and assembly 30 mounted thereon crosswise on the horizontal shaft 54 are also provided and may comprise the shifter slide 135 which is slidably mounted upon the cross shaft 54. The slide 135 is provided with slots 136 upon opposite sides 35 thereof within which a pair of blocks 137 are adapted to be positioned. The blocks 137 may be connected by suitable pin members 138 to the bifurcated arms 140 of a crank member 142 formed with an offset extension 144. The arm 144 of the crank connects with a shifter nut member 146 which has a screw-threaded rod 148 engaging a tapped opening 149 therein. The rod 148 is mounted for rotating movement in a bearing 150 secured to the cross bar 48 and carries 45 at its upper end a hand wheel 152. Thus by rotating the hand wheel 152 and either withdrawing or inserting the threaded end of the rod 148 in the shifter nut 146, the crank arm 142 will be rotated on its pivot and move the motor 50 and associated parts back and forth upon the cross shaft 54. The pivot 154 may be mounted in a suitable bearing 156 that is formed integral with the bracket 58. It will be obvious that the shifter plate 135 effects this motion by bearing 55 against a spacer 158 positioned on the end of the bearing portion 56a of the motor support 56.

While I have described the frame 10 as supported upon a pair of rollers 28 and 30 upon a single rail 32 which is usually adjacent the 60 switch point upon which it is desired to grind, I provide a further support in the form of a wheel 170 secured to the outer end of an outrigger member 172 extending sideways from the frame. The wheel 170 is thus adapted to ride upon the stand- 65 ard adjacent rail 32 of the track.

The outrigger assembly may include a wheel supporting axle 174 that is secured in one end of a tubular member 176. The tubular member 176 may be connected in any one of a plurality 70 of extended positions by an eye bolt 178 which extends through one of several spaced openings 180 in the tubular member and through a shaft portion 182 of a pivoting bracket 183. The bracket 183 is formed with a yoke portion hav- 75

ing the spaced arms 184 and 185 which carry a horizontally positioned pin member 186. The extension of the arms 184 and 185 form a bearing portion 187 which is mounted upon a stub shaft 188. The shaft 188 is adapted to be carried by a pair of right and left hand bracket members 189 and 190 that are fastened to the vertical wall of channel member 14 by suitable cap screws 192.

I mount right and left hand outrigger tipping brackets 194 and 196 upon the upper wall of channel 14 and position a nut member 198 therebetween, providing the same with suitable stud portions 199 to engage in the openings 200. I provide a drilled opening 202 in the stub shaft 186 and mount the lower reduced end 204 of the outrigger screw 206 therein. Thus the screw 206 may be rotatably mounted in the stub shaft 186. A lock nut 208 is secured to the lower end of the screw to fasten the same to the shaft 186. The screw member may extend through the nut 198 and carry a handle portion 209 which is fastened through a hole 210 at the upper end of the screw.

With the wheel 170 resting on one of the track rails 32 and the rollers 28 and 30 resting upon the other track rail 32, the entire machine may be tipped to a desired vertical angle by adjustment of the screw member 206 either up or down, thus providing an effective angle adjustment for the grinding wheel 108.

From the above and foregoing it will be apparent that a comparatively simple all purpose grinder has been provided, one which may be adjusted to provide almost any conceivable angle of grinding as well as any height within limit, of the grinding wheel or at any angle off the vertical. Each of the adjusting means provided are comparatively simple to operate and can easily be handled by a single operator. It will also be obvious that the entire mechanism may be moved to and fro as desired during a grinding operation.

In order to provide power for use in the vicinity of the grinder I provide a power take-off from the grinder shaft 82. For this purpose I have provided the friction cone 104 mounted on the end of the grinder shaft 82. The shaft support bracket 84 is provided with an extension 92b on one of the arms 92 provided with suitable bolt holes so that the bracket 220 may be bolted thereto. The bracket 220 may carry a friction disc 224 to frictionally engage the cone 104. The bracket may also carry the shaft 226 connected to the disc 224 and an eccentric arm 228 by means of which the friction disc 224 may be placed against the cone 104 or spaced therefrom as desired. The shaft 226 is connected to a suitable

flexible shaft 230 which may have a suitable work tool upon the end and thus the work tool may be driven from the motor E.

The details of the take-off mechanism may be similar to those shown in my application for patent Serial No. 103,497, which matured into Patent No. 2,106,034 on January 18, 1938, and be supported in the same manner upon the arm 92b of the bracket 84. It will be observed that in order to attach the flexible drive mechanism it is necessary to raise the grinding wheel to the position shown in Fig. 11 so that there is a proper clearance for these parts between the uprights of the frame.

While I have illustrated and described a specific embodiment of my invention, it will be apparent to those skilled in the art that changes and modifications may be made in the exact details shown, and I do not wish to be limited in any particular; rather what I desire to secure and protect by Letters Patent of the United States is:

1. An apparatus for grinding rails comprising a frame, a grinding wheel mounted on said frame, a support member for said grinding wheel means associated with said frame for adjusting said grinding wheel in any of a plurality of operative fixed vertical adjustments relative to the rails, said means including a bracket secured to the frame and having a plurality of tooth-engaging slots, a hand lever mounted on the frame and having a tooth engageable with said slots for providing locked engagement therewith, said means also including a crank member disposed within the frame and operatively associated with the grinding wheel support member and the hand lever and bracket whereby said crank member serves to apply the thrust for raising the grinding wheel vertically and also serves to support the grinding wheel in any of its plurality of operative positions.

2. An apparatus for grinding rails comprising a frame, a grinding wheel mounted on said frame, a support member for said grinding wheel carried by the frame, and having a slot in one end thereof, means associated with said frame for adjusting said grinding wheel in any of a plurality of operative fixed vertical adjustments relative to the rails, said means including a crank member disposed within the frame and operatively associated with the slot in the support member, whereby said crank member serves to apply the thrust for raising the grinding wheel vertically and also serves to support the grinding wheel in any of its plurality of fixed operative adjusted positions.

ARTHUR WILLIAM MALL.
